UNITED STATES PATENT OFFICE.

CARLOS A. SMITH, OF BELLAIRE, OHIO.

IRONING-TABLE FOR PRESSING-MACHINES.

980,688.

Specification of Letters Patent.

Patented Jan. 3, 1911.

Application filed November 27, 1909. Serial No. 530,224.

To all whom it may concern:

Be it known that I, CARLOS A. SMITH, a citizen of the United States of America, and resident of Bellaire, county of Belmont, 5 and State of Ohio, have invented certain new and useful Improvements in Ironing-Tables for Pressing-Machines, of which the following is a specification.

This invention relates to improvements in 10 ironing tables for laundry pressing or ironing machines, and it has for its primary object to provide an ironing table having improved means whereby the moisture contained by the clothes or garments ironed 15 thereon may be readily disposed of.

A further object is to provide an improved cushion or pad through which the moisture driven from the garments may readily pass.

20 Another object of the invention is to provide an improved form of bosom plate for use in ironing shirts, which plate is particularly adapted for use in connection with my ironing table when ironing shirts.

25 With these and other objects in view, the invention finally consists in the particular construction, arrangement and combination of parts which will hereinafter be fully described, reference being had to the accompanying drawings, forming a part of this 30 specification, in which—

Figure 1 is a top plan view of the invention; Fig. 2 is a longitudinal section on the line 2—2, Fig. 1; Fig. 3 is a cross section on 35 the line 3—3, Fig. 2; Fig. 4 is a top plan view of the bed-plate; Fig. 5 is a similar view of the rubber pad; Fig. 6 is an enlarged sectional view of a portion of the same; Fig. 7 is a top plan view of the foraminous 40 plate which is interposed between the rubber plate and the bed-plate; and Fig. 8 is a similar view of the bosom plate.

Referring to said drawings, in which like 45 reference characters designate like parts throughout the several views—1 indicates the bed-plate of the ironing table, the same being mounted upon the ordinary semi-rotatable supporting arm 2 carried by pedestal 3 of a pressing or ironing machine. The upper surface of said bed-plate is provided 50 with a series of grooves or channels 4 each of which inclines slightly from its opposite ends to a cross-groove 5 which inclines from its opposite ends to a drain-opening 6 from

which leads a flexible drain-pipe or hose 7. 55 Said grooves and drain-pipe are adapted for receiving and conducting to a suitable point the water collected from the clothes during the pressing or ironing process.

Resting upon the bed-plate 1 is a foraminous plate 8, preferably of wire netting, as shown, and superposed over said plate 8 is a heavy pad 9 of a soft resilient material, such as rubber, rubber-fabric, cork, or a cork and rubber composition, having a plurality of perforations 10 therein, as shown. Mounted over the pad 9 is one or a plurality of layers or thicknesses of cloth or soft padding 11 upon which the garments to be ironed are placed, as ordinarily. 70

In practice, the garment, which has previously been stretched over the top of the ironing table, is brought into contact with or pressure-applying relation to a heated ironing plate, as ordinarily, and the garment is ironed by the pressure and heat of said plate. The moisture in the garments is converted into steam or vapor when the heated plate contacts therewith, which steam or vapor is driven through the padding 11, 80 perforations 10 in the pad 9, and the wire netting, and in its passage is condensed. The condensed vapor follows, in the form of water, the grooves in the bed-plate 1, and is conducted away through the drain-pipe 7. 85

For preventing the material of which the pad 9 is composed from collapsing in such a manner as to partially or wholly close the perforations 10 thereof, a coil-spring 12 is fitted closely in each perforation. These 90 springs, while preventing the material from being pressed or crushed inward to clog said perforations, admit of the ready passage of water therethrough and yield to pressure with the material. 95

Since the fold-over portions of an open shirt bosom require separation in ironing, a dividing bosom plate is usually employed, said plate being inserted between said fold-over portions. The outer or multiple-ply 100 strip 13 and the underlying edge of the bosom hold a greater quantity of moisture than the other portions of the body of the shirt on account of the greater thickness of the goods; hence, in order to facilitate the 105 removal of this excess moisture, I provide a bosom plate 14 for insertion between the fold-over portions of the shirt, which plate

has a plurality of perforations 15 in the edge thereof which underlies said strip 13. The perforations admit of the passage therethrough of such moisture as is driven from 5 said strip 13.

In order to provide grasping means whereby the bosom plate may be held while holding the body or bosom of the shirt stretched, the bosom-plate 14 is formed with 10 an integral L-shaped extension 16, the lower edge of which parallels the folded or tucked under tail of the shirt, as shown in Fig. 1. Said lower edge is preferably turned or rolled to form a bead 17 whereby the operator may grasp the plate for forcing it into proper or squared position and for holding the same in place.

Having thus described my invention, what I claim as new, and desire to secure by Letters Patent, is—

- 20 1. An ironing table for laundry pressing machines, comprising a bed-plate provided with draining means, a foraminous plate located over said bed-plate, a pad of resilient material superposed over said foraminous plate, said pad having perforations therein, means for preventing clogging of said perforations, and a fabric covering for said pad.
- 25 2. An ironing table for laundry pressing machines, comprising a bed-plate provided with draining means, a foraminous plate located over said bed-plate, a pad of resilient material superposed over said foraminous plate, said pad having perforations therein,

coil springs fitted in said perforations, and a fabric covering for said pad.

3. An ironing table for laundry pressing machines, comprising a bed-plate having water collecting and conducting means, a 40 foraminous plate seated upon said bed-plate, a perforated pad of yieldable material seated upon said foraminous plate, means mounted in the perforations of said pad for maintaining the full capacities thereof, and a fabric 45 covering for said pad.

4. An ironing table for laundry pressing machines, comprising a bed-plate having water collecting and conducting means, a wire gauze overlying said bed-plate, a perforated pad of yieldable material overlying 50 said gauze, means for preventing restriction of the capacity of the perforations in the pad when the latter is subjected to pressure, and a covering for said pad.

5. An ironing table for laundry pressing machines, comprising a bed-plate having water collecting and conducting means, a wire gauze overlying said bed-plate, a perforated pad of yieldable material overlying 60 said wire gauze, coil springs fitted in the perforations of said pad for maintaining the full capacities thereof, and a covering for said pad.

In testimony whereof I affix my signature 65 in presence of two subscribing witnesses.

CARLOS A. SMITH.
